US00D665663S

(12) **United States Design Patent**
Krupa

(10) **Patent No.:** **US D665,663 S**
(b4) **Date of Patent:** **** Aug. 21, 2012**

(54) **BIODEGRADABLE, COMPOSTABLE FOOD CONTAINER**

(76) Inventor: **Calvin S. Krupa**, Greenfield, MN (US)

(**) Term: **14 Years**

(21) Appl. No.: **29/379,570**

(22) Filed: **Nov. 22, 2010**

Related U.S. Application Data

(62) Division of application No. 29/339,863, filed on Jul. 9, 2009, now Pat. No. Des. 627,635.

(51) **LOC (9) Cl.** **09-03**

(57) **CLAIM**

The ornamental design for a biodegradable, compostable food container, as shown and described.

DESCRIPTION

FIG. 1 is a top perspective view of a biodegradable, compostable food container showing the bowl portion of my design, separately, for clarity of detail;

FIG. 2 is a front elevational view thereof, with the rear, right, and left elevational views being mirror images thereof;

FIG. 3 is a top plan view thereof;

FIG. 4 is a bottom plan view thereof;

FIG. 5 is a bottom perspective view thereof;

FIG. 6 is a cross sectional view thereof taken along line 6-6 of FIG. 3;

FIG. 7 is a top perspective view of a biodegradable, compostable food container showing the combined bowl and lid portions of my new design;

FIG. 8 is a top perspective view of a biodegradable, compostable food container showing the lid portion of my design, separately, for clarity of detail;

FIG. 9 is a front elevational view of the lid portion of FIG. 8, with the rear, right, and left elevational views being mirror images thereof;

FIG. 10 is a top plan view of the lid portion of FIG. 8;

FIG. 11 is a bottom plan view of the lid portion of FIG. 8;

FIG. 12 is a bottom perspective view of the lid portion of FIG. 8; and,

FIG. 13 is a cross sectional view of the lid portion of FIG. 8 taken along line 13-13 of FIG. 10.
